UNITED STATES PATENT OFFICE.

ESECK C. MILLER, OF NEWARK, NEW JERSEY, ASSIGNOR TO IMPERIAL STOPPER COMPANY, A CORPORATION OF MAINE.

LIQUID-COMPENSATING DEVICE FOR BOTTLE-CAPPING MACHINES.

1,050,373.

Specification of Letters Patent. Patented Jan. 14, 1913.

Application filed June 29, 1911. Serial No. 635,914.

To all whom it may concern:

Be it known that I, ESECK C. MILLER, a citizen of the United States, residing at Newark, in the county of Essex and State 5 of New Jersey, have invented certain new and useful Improvements in Liquid-Compensating Devices for Bottle-Capping Machines, of which the following is a full, clear, and exact description.

10 This invention relates to bottling appliances, and more particularly to a compensating device of a novel type, which is characterized by great simplicity and cheapness of construction.

15 As is well known, in applying sealing devices to bottles, while the said bottles are supposed to be of uniform height and of uniform diameter of lip, in practice considerable variations exist, and in bottles of 20 cheap manufacture this difference in height for, let us say, pint bottles, may be one inch, or even more. Correspondingly, if the tool by means of which the head of the bottles are formed be carelessly manipulated, or for 25 other causes, the diameter of the head, and more especially, in so far as the application of a sealing cap, if that be used, is concerned, the lip, may vary quite materially. If then 30 a machine comprising, for example, a movable capping head have its bottle supporting table set for bottles of a certain height, and a bottle of greater height than that allowed for be placed on the table, such bottle will probably be broken unless some form of compensating mechanism or pressure releasing 35 device be provided. Conversely if the bottle be a little short and no compensation has been provided, such bottle will probably not be properly capped. Where a tapered cap 40 applying throat is used differences in the diameter of bottle lip have a similar effect. Various forms of compensating devices and pressure releasing mechanism have been devised from time to time for the purpose of 45 overcoming this difficulty, and some of these have been fairly successful in operation.

The principal object of the present invention is to provide a compensating mechanism based upon a principle new to this art, and 50 of great efficiency and reliability, while at the same time permitting of quite simple and inexpensive construction.

Various novel features and combinations 55 of parts are embodied in the exemplification of my invention shown in the accompanying

drawings, and these features and combinations will be hereinafter referred to and more particularly pointed out in the appended claims.

While I have shown one form of the device, I am aware that many variations and changes therein may be effected without departing from the spirit of the invention, and hence I do not desire to be limited or restricted except by the scope of the claims 60 65 appended hereto.

In the drawings which form a part hereof and in which like reference characters designate like parts throughout the several views: Figure 1 is a front elevation of a bottle capping machine involving one form of my 70 novel compensating mechanism, the latter being partly broken away to show some of the details of construction. Fig. 2 is a longitudinal section taken on the line II—II 75 of Fig. 1, the standard and bottling head of the capping machine being shown in side elevation.

Referring to the drawings; a base 1 of any suitable construction carries a standard 2 80 within which is, in this exemplification of my invention, the usual upright shaft 3, to which is secured a capping head 4. This head may be of any suitable or known construction, a number of capping heads having 85 been devised from time to time suitable for applying the various types of caps or stoppers to bottles. The head is adapted to be reciprocated by means of its supporting shaft 3 in a well known manner. 90

A combined casing and bracket broadly designated 5 is mounted on the standard, being preferably supported by a rib or shoulder 6 provided on the side of the standard, and being locked against lateral displacement by means of a set screw 7, or in any other suitable manner. In the interior of the casing is a chamber 8, preferably of cylindrical form, in which is disposed a plunger 9 neatly fitted thereinto so as to 100 form an effective liquid tight partition in the chamber which movable longitudinally thereof. This plunger is carried by a stud or shaft 10 which is firmly secured thereto; the lower extremity of the stud being preferably reduced in diameter as at 11 to provide a shoulder, and threaded so that the hub 12 of the plunger may be clamped firmly between this shoulder and a nut 13. The upper extremity of the stud 10 is also 110

preferably reduced in diameter and threaded as at 14 to afford a firm seat and connection with a table 15, this table preferably having the form of an inverted cup. The cup forming flange 16 of the table depends around an extension 17 which projects upwardly from the body of the bracket or casting; and this extension is bored for the reception of the shaft or stud 10, which preferably fits neatly therein, and is further annularly recessed as at 18 for the reception of a helical spring 19, the lower extremity of said spring being seated in the recess 18 and the upper extremity thereof bearing 15 against the table 15. The upper wall of the chamber 8 may be provided if desired with a depending lug 20 against which the hub 12 of the plunger is adapted to abut. The spring 19 is placed under some initial compression, and it is evident that as the table 15 is driven downwardly in the manner hereinafter described, the plunger 9 will be correspondingly depressed, and the compression of spring 19 will, of course, increase to some extent. The spring, however, 25 preferably has a considerable number of turns of relatively large diameter, so that this increase in pressure is not sufficiently great to be objectionable. The table may be recessed on its upper side for the reception 30 of a cushioning pad 21, of any suitable material, and a bottle 22 may be seated upon this pad.

The chamber 8 is, as aforesaid preferably 35 cylindrical and its axis is in alinement with that of the stoppering or capping head. Said chamber is provided with ports designated 23 and 24 at its respective upper and lower extremities, which ports communicate 40 with a suitable conduit 25. Conduit 25 in this instance extends partly around chamber 8, being separated therefrom by the wall 26. Below the plunger 9 is a preferably reciprocable valve 27, which in this instance has the form of a ring, said ring being provided with oppositely disposed and inwardly directed lugs 28 which project toward each other, and between which is mounted one end of a link 29. The valve 45 and link are secured together in any suitable manner, as by means of a pin 30; and the lower extremity of link 29 is in turn pivotally connected to a crank-arm 31, said arm being mounted upon a short rock-shaft 50 55 32 disposed in one side of a cap 33 which covers the lower extremity of the chamber 8; shaft 32 preferably being journaled through a lug 34 which extends laterally from the said cap. The crank arm 31 is 60 rigidly connected to this rock shaft, and the other extremity of said shaft has correspondingly secured thereto a second crank-arm 35. The free end of the latter arm is pivotally connected to a rod 36 which extends up in substantial parallelism with the

standard 2; the upper extremity of rod 36 being conveniently connected at 37 to a lug 38 which may form a part of the head 4. By reason of the construction shown therefore when the head 4 is caused to descend 70 rod 36 being secured thereto also moves downwardly an equal amount. This rotates the rock-shaft 32, and the latter in turn rotates crank-arm 31, and thereby moves the valve 27 downwardly, although 75 less rapidly than the head 4. The valve 27 when moved down a sufficient distance closes the ports 24.

It may be here stated that the chamber 8 and conduit or auxiliary chamber 25 together with the cap 33 are intended at all times to be substantially filled with suitable liquid. This liquid may be glycerin, various oils, or even water. It is preferable, however, to use some form of oil. Cap 33 is secured 85 to the under side of the casing by means of bolts 39, and the liquid holding chambers and passages are substantially liquid tight so that no evaporation of the liquid contained therein is apt to occur. Should any 90 liquid be lost by leakage, or for any other reason, the cavities may be refilled by removing the plug 40 which is disposed in a vent 41 in the upper side of the bracket, this vent preferably communicating with the 95 conduit or auxiliary chamber 25.

The operation of the device is as follows: Having placed a cap or stopper in the capping head 4, and a bottle 22 upon the pad 21, the capping head is caused to descend, and 100 the cap, if that be the form of stopper used, is forced down upon the head of the bottle in the usual manner. Thereafter the capping head and table 15 descend together through the instrumentality of the bottle 105 therebetween. In the meantime the valve 27 is being caused to move toward its ports 24 in the manner above described, and when the head has traversed a determined distance, these ports will be closed. The descent 110 of the plunger 9 causes liquid to flow through ports 24 from the chamber 8 into and up through the conduit, said liquid flowing thence through ports 23 into the upper portion of chamber 8, or in other words, into 115 the space above the plunger or partition 9. This flow of liquid continues while the bottle is being pushed downwardly until ports 24 are closed, in the manner aforesaid. Thereafter it is evident that no outlet exists 120 for the liquid below the plunger and as the liquid is substantially non-compressible, the plunger cannot descend farther and hence opposes the advance of the capping head. The parts are so arranged, however, that the 125 capping head has, at such time, almost reached the end of its stroke, there being but just sufficient length of travel left to insure firm application of the cap or stopper to the bottle head. Thereafter the head moves up- 130

wardly in the usual fashion, and the spring 19 causes the table 15 and bottle 22 to follow the head in its upward travel until the hub 12 encounters the depending lug or other 5 suitable stop 20, the head thereafter moving upwardly to its uppermost position preparatory for a repetition of the capping operation. It is obvious that the valve 27 should barely more than close the ports 24 upon 10 the completion of the downward stroke of the capping head in order that when the capping head moves upwardly in the manner described, ports 24 may be almost immediately uncovered, to thereby permit the 15 spring 19 to operate in the manner just described; since the upward movement of the table by said spring forces the plunger upwardly and thereby impels the liquid in the space above the latter through ports 23, conduit 25 and ports 24, to the space originally 20 occupied by said liquid.

It is evident that the stroke of the shaft 3 is of determined length and that therefore the capping head has a determined and fixed 25 travel. On the other hand, however, the stroke of the shaft or stud 10 is indeterminate, being dependent upon the length of bottle to be capped. The normal cycle of movements of the several parts may briefly 30 be stated as follows: Shaft 3 and head 4 start to move toward the bottle and the head engages the same; the table, plunger and connecting shaft 10 start to move, therefore, at some indeterminate later period; the 35 above parts all move together in manner aforesaid with equal velocity; then the table, plunger and shaft 10, cease to move owing to the action of the hydraulic lock; and the head and its supporting shaft 3 reach the 40 end of their downward stroke by moving a fixed and determined distance after the said hydraulic lock has been applied, thereby completing the application of the stopper or cap to the bottle. This mechanism differs 45 therefore radically from devices wherein fluid held in one compartment is utilized to resist the initial downward movement of a bottle supporting table and which fluid is released or allowed to flow into another compartment 50 after a predetermined spring regulated pressure has been applied to said table. The action of the present mechanism is positive, while that of such a mechanism as has just been referred to depends upon a spring. 55 Furthermore there is no tripping action involved in the present construction and the completion of the application of the cap to the bottle invariably takes place at a certain and definite point in the travel of the head, 60 as a result of which the operation of the machine as a whole is rendered less jerky and irregular.

Having described my invention, I claim:

1. A bottle stoppering machine comprising 65 a stopper applying head and a bottle

support adapted for relative movement with respect to each other, one of said parts being yieldingly mounted and the other of said parts having a determined travel, the yieldingly mounted part being displaceable by 70 the other through the instrumentality of the bottle to be capped, a casing adapted to hold liquid, a liquid displacing plunger in said casing, force transmitting means between said yieldingly mounted part and said plunger, and means for preventing displacement 75 of liquid by said plunger after the part having a determined travel has reached a determined point in said travel.

2. A bottle stoppering machine comprising 80 a stopper applying head and a bottle support adapted for relative movement with respect to each other, one of said parts being yieldingly mounted and the other of said parts having a determined travel, the 85 yieldingly mounted part being displaceable by the other through the instrumentality of the bottle to be capped, a casing adapted to hold liquid, a liquid displacing plunger in said casing, force transmitting means between 90 said yieldingly mounted part and said plunger, and means for preventing displacement of liquid by said plunger, said means comprising a valve and means for operating said valve in synchronism with a movement 95 of the part having a determined travel.

3. A stoppering machine comprising a yieldingly mounted member and a member having a determined travel, said members being adapted for relative movement with 100 respect to each other, a liquid holding casing, a plunger in said casing, movement of said yieldingly mounted part displacing liquid in said casing, and means co-acting with said liquid holding casing and plunger for 105 preventing said yieldingly mounted member from yielding after the member having a determined travel has reached a determined point in said travel.

4. A bottle stoppering machine comprising 110 a stopper applying head and a bottle support adapted for relative movement with respect to each other, one of said parts being yieldingly mounted and the other having a predetermined travel, the yieldingly mounted part being displaceable by the other through the instrumentality of the bottle to be capped, a casing adapted to hold liquid, a plunger in said casing, connections between 115 said plunger and said yieldingly mounted part, whereby movement of the latter displaces said plunger and thereby displaces liquid in a part of said casing, and positively acting means for arresting the displacement of fluid in said part of said 120 casing.

5. A bottle capping mechanism comprising 125 a reciprocable capping head, a bottle support, a ported receptacle adapted to hold liquid, means for forcing liquid through a 130

port in said receptacle, said means being operable by a movement of said bottle support, and means for closing said port at a determined point in the travel of said capping head.

6. A bottle capping mechanism comprising a reciprocable capping head, a bottle support, a ported receptacle adapted to hold liquid, means for forcing liquid through a port in said receptacle, said means being operable by a movement of said bottle support, means for closing said port at a determined point in the travel of said capping head, and means whereby said liquid may return to the portion of said receptacle from which it was displaced.

7. In a stoppering machine having a compensating device, a ported casing adapted to hold a liquid, a valve adapted to close a port in said casing, a plunger adapted to displace liquid through said port, means adapted to co-act with the receptacle to be stoppered for depressing said plunger, and means for actuating said valve, said last mentioned means being operable by the first mentioned means.

8. In a bottle capping machine, a capping head, a yieldingly mounted support for the bottle, a casing having therein a chamber and a conduit leading substantially from one end of said member to the other, and having ports in the walls of said chamber connecting with said conduit, a piston in said chamber operable by said bottle support, and a valve for one of said ports.

9. A bottle capping mechanism comprising a reciprocable member having a stroke of determined length, a reciprocable mem-

ber operable by the first mentioned member through the instrumentality of the bottle to be capped, said last mentioned member having a stroke of indeterminate length, and a hydraulic device, constituting a lock, for limiting the movement of said second member, said first mentioned member being movable through a determined portion of its stroke after the second member has ceased to move.

10. A bottle capping mechanism comprising a reciprocable member having a stroke of determined length, a reciprocable member operable by the first mentioned member through the instrumentality of the bottle to be capped, said last mentioned member having a stroke of indeterminate length, and a hydraulic device, constituting a lock, for limiting the movement of said second member.

11. A bottle capping mechanism comprising a reciprocable member having a stroke of determined distance, a reciprocable member operable by the first mentioned member through the instrumentality of the bottle to be capped, said last mentioned member having a stroke of indeterminate length, and a hydraulic device, for limiting the movement of said second member, said device comprising a hollow ring shaped valve, and a ported structure with which said valve operates.

In witness whereof, I subscribe my signature, in the presence of two witnesses.

ESECK C. MILLER.
